Des. 1704

G. B. Halsted, of New York, N.Y.
Letters Patent, No 1704, dated, Jan'y 13, 1863

The schedule referred to in these Letters Patent and making part of the same

To all whom it may concern:

Be it known that I, G. B. Halsted, of the City, County and State of New York, have invented or produced a new and original design for a jacket or Draught Chamber for Coal Oil Lamps, and I do hereby declare that the following is a full, clear and exact description of the same, reference being had to the accompanying drawings making a part of this specification in which

Figure 1, is a side view of the jacket or draught chamber constructed according to my design.

Figure 2, an end view of the same.

Figure 3, a plan or top view of the same.

Figure 4, a perspective view of the same.

Similar letters of reference indicate corresponding parts in the several Figures.

A, represents the lower part of the jacket or draught chamber which is of quadrilateral form, the ends a. a. having a vertical position, the sides b. b. being inclined.

The upper part B, of the jacket or draught chamber has vertical parallel sides c. c. which project upward from the tops of the sides b. b. and a rounded semi-circular

Dec. 1704

or arched top d, which has a slot e, made longitudinally in it extending nearly its whole length. The ends f.f. of the part B, are inclined at an angle of about 45° and they are rounded upward at their extreme ends as shown at g. This inclination of the ends f.f. of the part B, causes it to project considerably beyond the ends of the lower part A, as shown clearly in Figure 1.

The inclined sides b.b. of the part B, have each two vertical slots h.h., of rectangular form made in them to serve as draught passages.

Having thus described my invention what I claim as new and desire to secure by Letters Patent, is,

The configuration of the parts herein shown and described to form a new and original design for a jacket or draught chamber for a Coal Oil Lamp.
